United States Patent Office

Des. 224,940

Patented Oct. 17, 1972

224,940

SPOON OR SIMILAR ARTICLE

Marion Weeber, New York, N.Y., assignor to American Home Products Corporation, New York, N.Y.

Filed May 3, 1971, Ser. No. 140,018

Term of patent 14 years

Int. Cl. D7—03

U.S. Cl. D54—12

FIG. 1

FIG. 2

FIG. 3

FIG. 4

FIG. 1 is a front elevational view of a spoon or similar article showing my new design.

FIG. 2 is a side elevational view thereof.

FIG. 3 is a back elevational view thereof.

FIG. 4 is an enlarged cross-sectional view taken on line 4—4 of FIG. 1.

I claim:

The ornamental design for a spoon or similar article, as shown.
